COSMETIC TRAY

Louis F. Kolarik, 606 Ardmore Ave., Erie, Pa.

Filed Feb. 13, 1961, Ser. No. 63,928

Term of patent 14 years

(Cl. D86—10)

Fig. 3

FIG. 1 is an isometric view of a cosmetic tray showing my new design;

FIG. 2 is another isometric view thereof as seen from below FIG. 1; and

FIG. 3 is a side elevational view thereof.

The essential features of my design are shown in full lines on the drawing.

I claim:

The ornamental design for a cosmetic tray, as shown and described.
